FRictional Hinge for Windows or the Like Pivotal in Horizontal or Vertical Direction

Alf Otto Hellqvist, Vedevag, Sweden
Application April 5, 1943, Serial No. 481,818

In Sweden September 30, 1942

3 Claims. (Cl. 16—140)

The present invention relates to a frictional hinge for windows or the like pivotal in horizontal or vertical direction, especially for so-called perspective windows or the like, which hinge may be adapted to the size and weight of the window in such a manner that the frictional parts of the hinge are not exposed to excessive load.

According to the invention the hinge shank which is fixed to the window casement is pivotally journalled in the hinge shank which is fixed to the window frame, and is provided with a pin-shaped extension, on which are placed the necessary number of interchangeable frictional disks which are pressed against each other by means of a spiral spring, said disks being alternately pivoted and fixed respectively on the pin-shaped extension.

The disks which are pivotally mounted on the pin-shaped extension may, according to this invention, be connected with the hinge shank fixed to the window frame by providing them with holes which are engaged by a pin secured to said hinge shank and common for all of these disks. The other disks, which are fixed to the pin-shaped extension, may be provided with parts projecting into their central openings, which projections engage longitudinal grooves provided in the pin-shaped extension.

According to the invention, the pin-shaped extension may consist of a member fixed to the hinge shank of the window casement by means of screws and a projecting part engaging a groove or the like in said hinge shank.

Two embodiments of the frictional hinge according to the invention are illustrated on the accompanying drawings.

Figs. 1 and 2 show the front and side view, respectively, of a window pivotal in the horizontal direction and provided with two frictional hinges according to the invention.

Fig. 3 is an enlarged side view of the frictional hinge according to Figs. 1 and 2, and

Fig. 4 is a section along the line IV—IV in Fig. 3.

Figs. 5 and 6 show the pin-shaped extension in detail plan and side views, while

Figs. 7 and 8 show both kinds of disks in side view.

Fig. 9 is a side view of a modified embodiment of the frictional hinge.

1 is the window casement, which is pivotally journalled about the axis 2—2 in the window frame 3 by means of two frictional hinges.

One shank 5 of the frictional hinge is fixed to the casement 1 by means of screws or the like,

whereas the other shank 4 is secured to the window frame 3 in the same way. By means of screws 6 and a projecting part or rib 8 engaging a groove 7 in the shank 4 a pin 9 is fixed to the shank 5. The pin 9 is provided with a flange 10 forming a spacer piece or member between the shanks 4, 5 and having a hub portion 11, by means of which the shank 5 is pivotally journalled on the shank 4.

The disk 12 shown in Fig. 7 being non-rotatable in relation to the shank 4 and having a central opening 14 is provided with a hole 13 which is engaged by a pin 15 secured to the shank 4 when the disk is pushed on to the pin 9. The other disk 16 shown in Fig. 8 being non-rotatable in relation to the pin is pushed on to the pin 9 by means of the central opening 17 in such a manner that projections 18 in the opening engage longitudinal grooves 19 in the pin.

The disks 12 and 16 which are alternately pushed on to the pin 9 are pressed together by means of a spiral spring 21, one end of which abuts against the disks and the other end against a washer 20, the spring 21 being tensioned by means of a screw 22 screwed into the pin 9.

The number of the disks 12 and 16 is adapted to the size and weight of the window.

The screw 22, a screwed-on nut or the like may be used for the adjustment of the tension of the spring 21, as shown in Figure 4.

According to Fig. 9 it is also possible to tension the spring 21 by means of a washer 23, which is pushed on to the pin 9 and the extended pin 15 and is held in position by means of split pins 24.

Having now particularly described the nature of my invention and the manner of its operation what I claim is:

1. A hinge for pivoting a closure to a closure frame and for frictionally holding them in relative adjusted position which comprises, a first hinge shank adapted to be fixed to a closure, a second hinge shank adapted to be fixed to a closure frame, means fixed to and extending from said first hinge shank defining in coaxial succession a flange forming a spacer member, a hub, and a key-way, said second hinge shank being pivotally mounted over said hub and spaced from the first hinge shank by said spacer member, a pin fixed to and extending from said second hinge shank parallel to said key-way, a plurality of friction disks mounted on said key-way for free axial movement, a first group of said disks being keyed against rotation with respect to said key-way, a disk intermediate each pair of disks of the

first group mounted for free axial movement and rotation on said key-way and engaged by said pin so that the disks of the first group are held against rotation relative to the key-way and the other disks are rotatably mounted with respect to the key-way but held against rotation relative to the second hinge shank by said pin, and a spring on said key-way acting to compress all of said disks axially and to hold said second hinge shank against said spacer member in position over said hub.

2. A hinge according to claim 1 in which said

spring is helical and is disposed about the free end of said key-way, and wherein the end of the spring remote from the end acting on the disks abuts against a washer fixed to said key-way.

3. A hinge according to claim 1 in which the means defining in coaxial succession the spacer member, the hub and the key-way is secured to said first hinge shank by means of screws, and is provided with a rib cooperating with a groove 10 in said hinge shank.

ALF OTTO HELLKVIST.
